UNITED STATES PATENT OFFICE.

JOSEPH KONIGSBERG, OF NEW YORK, N. Y., ASSIGNOR TO LENA KONIGSBERG, OF NEW YORK, N. Y.

DIESTOCK.

1,423,945.

Specification of Letters Patent. Patented July 25, 1922.

Application filed August 24, 1920. Serial No. 405,574.

To all whom it may concern:

Be it known that I, JOSEPH KONIGSBERG, a citizen of the United States, and resident of the borough of Manhattan, in the city and State of New York, have invented a new and useful Improvement in Diestocks, of which the following is a specification.

This invention relates to an improvement in die stocks and has for its object to provide a device which will more readily center the cutting chasers on the pipe to be threaded and maintain the same throughout the cutting operation, so that a proper and accurate thread may be cut thereon.

Another object is to provide a structure having one centering device located at a distance from the cutting chasers and another centering device located between the first named device and immediately in front of the cutting chasers.

Another object is to provide an intermediate centering device having a plurality of radially movable arms, a common means for actuating the arms and a means for maintaining them in a fixed relative position.

Another object is to provide certain improvements in the form, construction and arrangement of the several parts whereby the above named and other objects may be effectively attained.

A practical embodiment of my invention is represented in the accompanying drawings, in which

Fig. 1 represents a plan view of a die stock having my improved centering devices applied thereto.

Fig. 2 represents a front elevation of the same.

Fig. 3 represents a vertical section taken in the plane of the line III—III of Fig. 1, looking in the direction of the arrows.

Fig. 4 represents a rear elevation of the die stock, portions of it being broken away to show more clearly the parts within, and

Fig. 5 represents a vertical central section taken in the plane of the line V—V of Fig. 1, looking in the direction of the arrows.

The die stock to which my improved centering devices are applied is of well-known and approved construction and I deem it necessary to describe only such parts as will give a clear understanding of the application of my invention thereto.

The die head is denoted by 1, the cutting chasers by 2 and the leader screw in the form of a barrel by 3.

One pipe centering device comprises a frame 4 carrying radially movable guide blocks 5, in the present instance three are shown, located at a distance in advance of the cutting chasers 2, and a screw threaded nut 6 which is arranged to travel on the leader screw 3.

A cam plate 7 is secured in rotatable adjustment on the frame 4, and is provided with eccentric segments 8 arranged to slide in slots 9 in the blocks 5, and thereby control the radial movement of the blocks. The cam plate 7 is rotatably secured on the frame 4 by means of a ratchet-wheel 10, which is threaded on a tubular hub 11 formed integral with the frame 4, and fixed against rotation by a screw 12, which passes radially through the ratchet-wheel and threaded into the hub 11.

To provide for a rotary adjustment of the ratchet-wheel 10, the hub 11 has a series of screw threaded holes 13, as shown in Fig. 4.

In order to lock the cam plate 7 and blocks 5 in a relatively fixed position, the cam plate is provided with a laterally extending lug 14 in which is positioned a pawl 15 arranged to engage the ratchet-wheel 10. The shank 16 of the pawl 15 is screw threaded to receive a thumb nut 17 which is adapted to engage the lug 14 to take up any lost motion between the pawl and ratchet-wheel and hold the cam plate and blocks against movement.

The leader screw barrel 3, in the present instance, is shown secured to the die head 1 by means of screws 18 threaded into ears 19 on the leader screw barrel. The securing of the leader screw barrel to the die head is not an essential feature toward the successful operation of my invention, since the barrel may be formed integral with the die head and provided with means other than being screw threaded by which the frame 4 of the centering device above described may be retained.

A second pipe centering device is located immediately in front of the cutting chasers 2 and comprises a cup-shaped ring 20 carrying radially swinging curved arms 21, each

- of which is pivoted at 22 and arranged to swing through curved guide slots 23 in the leader screw barrel 3, one side of each of which slot bears against the arms to guide them in movement and hold them in position in contact with the pipe. The ring 20 is retained in rotatable adjustment against the die head 1 by means of a ratchet-wheel 24, which is screw threaded on the barrel 3.
- 10 The ring 20 with its arms 21 is locked in a fixed relative position by means of a pawl 25 pivoted at 26 in a lug 27 extending laterally from the ring 20 and arranged to engage the ratchet-wheel 24 as clearly shown 15 in Fig. 3.

Thus it will be seen that by locating a plurality of centering devices in advance of the cutting chasers, and particularly one immediately in advance of the chasers, the die 20 head will place the chasers in a proper position to operate on the pipe to be threaded without any action on the part of the operator to center the chasers, since there is approximately no tendency toward a lateral 25 movement of the die stock in the hands of the operator.

It is well-known in the art of pipe cutting, that the operator depends entirely upon his skill in starting the cutting chasers on the 30 pipe so that an accurate thread may be cut thereon, and since the common pipe centering devices now in use are located a distance in front of the cutting chasers, a maximum amount of lateral movement is allowed the 35 die head at the end of a pipe.

The construction and arrangement of my centering devices with respect to the cutting chasers, reduces to a minimum the lateral movement of the die head and thereby the 40 chasers at the end of the pipe to be threaded.

It is obvious that various changes may be resorted to in the form, construction and arrangement of the several parts without departing from the spirit and scope of my invention, and hence I do not intend to be limited to the details herein shown and described except as they may be specifically included in the claims.

What I claim is:

- 50 1. The combination with a stock, of one centering device located at a distance from the cutting chasers and another centering device located between the first named device and the cutting chasers, said intermediate device comprising a plurality of swingingly movable arms having a common operating means, and a ratchet and pawl connection for maintaining said arms in a relatively fixed position.
- 55 2. The combination with a stock having a leader screw, of one centering device located at a distance from the cutting chasers and another centering device carried by the leader screw located in close proximity to the cutting chasers and between the first

named device and the cutting chasers, said intermediate device comprising a plurality of swingingly movable arms having a common operating means, and a ratchet and pawl connection for maintaining said arms in a relatively fixed position.

3. The combination with a stock, of one centering device located at a distance from the cutting chasers, said device comprising a plurality of radially movable blocks having a common operating means, said means being controlled by a ratchet and pawl connection for maintaining said blocks in a relatively fixed position, and another centering device located between the first named device and the cutting chasers, said intermediate device comprising a plurality of swingingly movable arms having a common operating means, said means being controlled by a ratchet and pawl connection for maintaining said arms in a relatively fixed position.

4. The combination with a stock having a leader screw, of one centering device located at a distance from the cutting chasers, said device comprising a plurality of radially movable blocks having a common operating means, said means being controlled by a ratchet and pawl connection for maintaining said blocks in a relatively fixed position, and another centering device carried by the leader screw located in close proximity to the cutting chasers and between the first named device, said intermediate device comprising a plurality of swingingly movable arms having a common operating means, said means being controlled by a ratchet and pawl connection for maintaining said arms in a relatively fixed position.

5. The combination with a stock, of a centering device located immediately in advance of the cutting chasers, said device comprising a plurality of swingingly movable arms having a common operating means, and a ratchet and pawl connection for maintaining said arms in a relatively fixed position.

6. The combination with a stock having a leader screw, of a centering device carried by the stock located immediately in advance of the cutting chasers, said device comprising a plurality of swingingly movable arms having a common operating means and a ratchet and pawl connection for maintaining said arms in a relatively fixed position.

7. The combination with a stock, of a centering device located at a distance from the cutting chasers, said device comprising a plurality of swingingly movable blocks having a common operating means, said means being controlled by a ratchet and pawl connection for maintaining said blocks in a relatively fixed position.

In testimony, that I claim the foregoing as my invention, I have signed my name, this 19th day of August 1920.

JOSEPH KONIGSBERG.
